UNITED STATES PATENT OFFICE

166,078

STEP STOOL

Bertis F. Hamilton, Columbus, Ind.

Application August 21, 1950, Serial No. 11,863

Term of patent 14 years

(Cl. D15—1)

To all whom it may concern:

Be it known that I, Bertis F. Hamilton, a citizen of the United States, residing at Columbus, Bartholomew County, Indiana, have invented a new, original, and ornamental Design for a Step Stool, of which the following is a specification, reference being had to the accompanying drawing, forming part thereof.

Fig. 1 is a front elevation of a step stool embodying my new design; Fig. 2 is a side elevation of the step stool showing the ladder in extended position; and Fig. 3 is a plan view of the stool with ladder extended.

I claim:

The ornamental design for a step stool, as shown.

BERTIS F. HAMILTON.
